(57) **CLAIM**

The ornamental design for a chalk line with handle, as shown and described.

DESCRIPTION

FIG. 1 is a front perspective view showing the chalk line;
FIG. 2 is a front view according to FIG. 1;
FIG. 3 is a back view according to FIG. 1;
FIG. 4 is a left side view according to FIG. 1;
FIG. 5 is a right side view according to FIG. 1;
FIG. 6 is a top view according to FIG. 1;
FIG. 7 is a bottom view according to FIG. 1;
FIG. 8 is a front view according to FIG. 2, illustrating a crank handle in an open position;
FIG. 9 is a left side view according to FIG. 8;
FIG. 10 is a right side view according to FIG. 8;
FIG. 11 is a front view of a first variant according to FIG. 1;
FIG. 12 is a back view according to FIG. 11;
FIG. 13 is a left side view according to FIG. 11; and,
FIG. 14, is a right side view according to FIG. 11.
The broken line showing of environment is for illustrative purposes only and forms no part of the claimed design.
